CLAIM

The ornamental design for a vascular model, as shown and described.

DESCRIPTION

FIG. 1 is a front view of a vascular model showing our new design;

FIG. 2 is a top plan view thereof;

FIG. 3 is a left side view thereof;

FIG. 4 is a right side view thereof;

FIG. 5 is an enlarged top plan view thereof;

FIG. 6 is an enlarged left side view thereof, rotated by 90degrees;

FIG. 7 is an enlarged right side view thereof, rotated by 90degrees;

FIG. 8 is a cross sectional slice, taken along line 8-8 of FIG. 1;

FIG. 9 is a cross sectional slice, taken along line 9-9 of FIG. 1;

FIG. 10 is a cross sectional slice, taken along line 10-10 of FIG. 1;

FIG. 11 is a cross sectional slice, taken along line 11-11 of FIG. 1;

FIG. 12 is a cross sectional slice, taken along line 12-12 of FIG. 1;

FIG. 13 is a cross sectional slice, taken along line 13-13 of FIG. 1;

FIG. 14 is a cross sectional slice, taken along line 14-14 of FIG. 1;

FIG. 15 is a cross sectional slice, taken along line 15-15 of FIG. 1; and,

FIG. 16 is a cross sectional slice, taken along line 16-16 of FIG. 1.

The rear view is omitted, because it is a mirror image of the front view. The bottom plan view is omitted because it is an identical image to the top plan view. The surface shading shown in the figures illustrates transparency.
